[57] CLAIM

The ornamental design for an instrument for sensing magnetic variations in the atmosphere, as shown.

DESCRIPTION

FIG. 1 is a perspective view of an instrument for sensing magnetic variations in the atmosphere showing my new design;

FIG. 2 is a top plan view thereof;

FIG. 3 is a typical side elevational view thereof; and

FIG. 4 is a bottom plan view thereof.

*Fig. 2.**Fig. 1.**Fig. 3.**Fig. 4.*
